(57) **CLAIM**

The ornamental design for a healing abutment with concave conical end section, as shown and described.

DESCRIPTION

FIG. 1 is a top, front, right axonometric view showing our new design.

FIG. 2 is a top, rear, left axonometric view showing our new design.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

1 Claim, 6 Drawing Sheets

FIG. 1

FIG. 2

FIG. 3

FIG. 4

FIG. 5

FIG. 6

FIG. 7

FIG. 8
